UNITED STATES PATENT OFFICE

95,135

DESIGN FOR A MECHANICAL PENCIL

Otto Huber, Astoria, N. Y., assignor to Eagle
Pencil Company, New York, N. Y., a corpora-
tion of Delaware

Application January 16, 1935, Serial No. 54,882

Term of patent 7 years

To all whom it may concern:

Be it known that I, Otto Huber, a citizen of
the United States of America, residing at 2708
Ditmas Avenue, Astoria, Long Island, N. Y., have
invented a new, original, and ornamental Design
for Mechanical Pencils, of which the following
is a specification, reference being had to the
accompanying drawing, forming part thereof, in
which

Figure 1 is a plan view of a mechanical pencil
showing my new design.

Figure 2 is a side elevation of the pencil.

I claim:

The ornamental design for a mechanical pen-
cil, as shown.

OTTO HUBER.
